FIGURE 1 is a perspective view of a utensil handle and tang showing my new design as used as part of a spoon;

FIGURE 2 is a fragmentary perspective view thereof;

FIGURE 3 is a fragmentary side elevation view thereof on an enlarged scale;

FIGURE 4 is a top plan view thereof on the same scale as in FIGURE 3;

FIGURE 5 is a bottom plan view thereof on the same scale as in FIGURE 3; and

FIGURES 6 through 11 are section views of the handle portion at the respective section lines 6-6 through 11-11 of FIGURE 4.

The essential features of my design are shown in the full line portions of the handle and tang, and more particularly in the specific configuration of the handle portion. The broken line showing of a spoon bowl is for illustrative purposes only.

I claim:

The ornamental design for a utensil handle and tang, as shown and described.
